UNITED STATES PATENT OFFICE.

EMIL ZUCKERMAN, OF NEW YORK, N. Y.

HINGE.

1,280,357.

Specification of Letters Patent.

Patented Oct. 1, 1918.

Application filed December 14, 1914. Serial No. 877,154.

To all whom it may concern:

Be it known that I, EMIL ZUCKERMAN, a citizen of the United States, residing at New York city, in the county of the Bronx and 5 State of New York, have invented certain new and useful Improvements in Hinges, of which the following is a specification, such as will enable those skilled in the art to which it appertains to make and use the 10 same.

This invention relates to hinges and particularly to what are called invisible or concealed hinges and more particularly to hinges of the class such as are described and 15 shown in Letters Patent of the United States granted to me Sept. 24, 1912, No. 1,039,628, and Aug. 25, 1914, No. 1,108,308.

The object of the invention is to provide a new and improved hinge for use on pianos, 20 doors, furniture, cabinet work and other articles and devices on which a hinge is used, and without danger of binding the hinged members.

A further object of the invention described 25 and claimed herein, is to render hinges of this class more durable and stronger, and simple in construction and operation and to enable same to be made entirely of steel stampings or stampings of any other metal, 30 from the smallest size for use on pianos to the largest size for use on heavy doors. I accomplish the desired result by the use of links disposed and actuated in inverse order to other links forming a connection between 35 the two main parts or attaching members of the hinge. By applying movable inverted guiding means, I am enabled to construct the hinges in all sizes without the use of grooves or slots as guiding means for the connecting 40 members. As no grooves or slots are required in the design and construction herein shown, the use of soft and brittle cast metal parts are unnecessary, and the result of stamped metal construction is a cheaper and 45 a stronger hinge.

As shown in the accompanying drawings, use is made of attaching members arranged one for attaching to a fixed part and the other to a movable part of the device on 50 which the hinge is to be used, a connection for connecting the said attaching members with each other, consisting of pivotally connected movable members; said connection pivotally secured near one side of each of 55 the attaching members, and guiding members pivotally secured near the other side of

each of the attaching members and to the said connection.

A practical embodiment of the invention is represented in the accompanying drawings forming a part of this specification, in which similar characters of reference indicate corresponding parts in all the views. 60

Figure 1 is a sectional plan view of the hinge as applied to a door and a door frame 65 in a closed position;

Fig. 2 is a similar view of the same with the door partly open;

Fig. 3 is a like view of the same with the door fully open;

Fig. 4 is an inner side view of the same shown in a closed position;

Fig. 5 is a front view of the same shown in an open position;

Figs. 6 and 7 are sectional plan views of 75 modified forms of the hinge;

Figs. 8 and 9 show the connecting link and stop as indicated in Figs. 1 and 6;

Fig. 10 is a perspective view of one of the 80 attaching members;

Figs. 11, 12, 13, 14 and 15 are views of a different type of hinge, but provided with the inverted guiding means which is a part of my invention;

Fig. 16 is a sectional plan view of the 85 hinge shown and described in Letters Patent of the United States granted to me Aug. 25, 1914, No. 1,108,308, excepting that I substitute the inverted guiding means which is a part of this invention instead of the guiding 90 means shown in the above mentioned patent.

As illustrated in Figs. 1, 2, 3, 4 and 5, the hinge is shown applied to a fixed member or door casing *a* and a movable member or door *b*, and the hinge is provided with attaching members *c* and *d*, of any approved construction and material, but preferably of sheet metal stamped into the required form as shown in Figs. 4 and 10. The attaching members are mortised in the adjacent ends of the door casing *a* and the door *b* and fastened thereto by screws *e* through the flanges forming the front face of the attaching members, as shown in Figs. 4 and 5. Near the outer side of the attaching member *c* or that side toward which the door swings in opening, is arranged a vertically disposed pivot *f* on which is mounted to swing the U-shaped link *g*, and a similar link *g*¹ is mounted to swing on a vertically 100 disposed pivot *f*¹ attached near the outer side of the attaching member *d*. The links *g* and 105

80

90

95

100

105

110

g^1 cross one another, and the free end of the link g extends into the attaching member d , while the free end of the link g^1 extends into the attaching member c . Near 5 the inner side of the attaching member c , or that side parallel with and opposite the outer side thereof is arranged a vertically disposed pivot h on which is mounted to swing the link i , and a similar link i^1 is 10 mounted to swing on a vertically disposed pivot h^1 attached near the inner side of the attaching member d . The free end of the link i is pivotally connected to the free end of the link g^1 by means of a pin j , while the 15 free end of the link i^1 is pivotally connected to the free end of the link g by means of the pin j^1 . The link g and the link i are connected with each other by means of the link k pivotally connected to both by the pins l 20 and l^1 . The link g^1 and the link i^1 are similarly connected with each other by means of the link k^1 pivotally connected to both by the pins l^2 and l^3 . It will be noticed that the link k is attached to the link i about centrally the latter's length and to the link g near the end thereof which is pivoted to the attaching member c , and that the link k^1 is attached similarly to the links i^1 and g^1 . It is understood that the pins j , j^1 , l , l^1 , l^2 25 and l^3 have no connection with the attaching members. It will be noticed that the series of links g , g^1 , i , i^1 , k , k^1 may be arranged one over the other as shown in Figs. 4 and 5 and connected in the manner described, so 30 as to provide any desired strength, according to the use of the hinge on light or heavy doors or other devices on which hinges are used.

It is understood that the links g and g^1 35 are the main connecting links, the links k and k^1 are the supplementary connecting links, and the links i and i^1 are the guiding links, which by their connection with the main and supplementary connecting links, 40 insure working in unison of the said main and supplementary connecting links on opening and closing the door. By the arrangement described, each attaching member c or d is provided with a pair of links g , i or g^1 , i^1 and the pair of links in each attaching member is connected to the pair of links in the other attaching member at their free 45 ends by means of pivots or pins, and also the pair of links connected with each attaching member are connected with each other by a connecting link. When the door b swings into open position the links i and i^1 swing outwardly and the links k and k^1 move outwardly toward the front of the 50 respective attaching members to which they are connected owing to the action of the main connecting links g and g^1 which also swing outwardly; and the supplementary connecting links k and k^1 overlie the main connecting links g and g^1 at the time the 55

door is swung into a completely open position, so that the door is firmly supported while in open position. The guide links i and i^1 by their connections with the main connecting links g and g^1 and the supplementary connecting links k and k^1 insure working in unison of the connecting links, and cause the attaching members to separate and come together uniformly and also prevents the hinged members from binding, in 60 opening and closing the door or other device on which the hinge is used. The free ends of the main connecting links g and g^1 , by reason of their shape, form stops g^2 and g^3 of which the stop g^2 is adapted to be engaged by the pivot pins f and f^1 while the stop g^3 is adapted to be engaged by the pins f^1 and f^2 at the time the hinge swings into 65 open position as indicated in Fig. 3. These stops limit the opening movement of the hinge, and also assist in relieving the hinge of undue strain. The supplementary connecting links k and k^1 are provided with lugs or stops k^2 and k^3 formed of a portion of the said links extending beyond the pivot pins l and l^1 , and the said lugs are adapted to be engaged by the pivot pins h , h^1 at the time the hinge moves into open position as indicated in Fig. 3. These lugs or stops limit the opening movement of the hinge, 70 and assist in relieving the hinge of undue strain, and are also designed to prevent the pins j and j^1 from swinging beyond dead center of pins h , h^1 or h^1 , h^2 when the hinge swings into open position as shown in Fig. 3. It will be noticed that the supplementary connecting links k and k^1 are so designed as to cover both ends of the pivots j and j^1 at 75 all times during the operation of the hinge. If the link members are laid one over the other in the manner shown in Figs. 4 and 5, this feature is of economic advantage from a manufacturing point of view, as the said pivot pins j and j^1 are held in place without riveting the ends and without danger of said 80 pins working out of position after the link members are assembled.

In Fig. 6 I show a slight modification of the hinge. Instead of the lugs or stops k^2 and k^3 shown in Figs. 1, 2, 3 and 8, and forming a part of the supplementary connecting links k and k^1 , I substitute therefor notches k^4 and k^5 of which the notch k^4 is adapted to be engaged by the pivot pin j , while the notch k^5 is adapted to be engaged by the pivot pin j^1 at the time the hinge swings into open position. These notches k^4 and k^5 serve the same purpose as the lugs k^2 and k^3 and are merely variations of the latter.

In Fig. 7 I show a further modification 125 of the hinge. Whereas in Figs. 1, 2, 3 and 6, I show the supplementary connecting links attached at one of their ends to the guiding links, about midway the latter's length, in Fig. 7 I show said supplementary connect-

130

ing links h and h^1 connected at one of their ends to the pivot pins j and j^1 connecting the free ends of the guiding links i and i^1 with the free ends of the main connecting links 5 g and g^1 . I do not show any stops or lugs to limit the opening movement of this hinge, but lugs similar to those shown in Fig. 1 may be attached to the supplementary connecting links h and h^1 . It will be noticed 10 that by the arrangement herewith described two of the pivot pins are dispensed with. Also that by reason of the connection of the supplementary connecting links with the pivot pins j and j^1 , the said supplementary 15 connecting links may be considered as being connected with either the guiding links i and i^1 , or the main connecting links g and g^1 , or with both the guiding and the main connecting links.

20 In Figs. 11, 12, 13, 14 and 15, I show the inverted guiding means which is a part of my invention applied to a hinge different from that shown in Figs. 1, 2, 3, 4, 5, 6 and 7. The hinge is shown applied to a 25 fixed member A and a movable member B, and the hinge is provided with attaching members C and D. As shown in Figs. 14 and 15, the attaching members are mortised in the adjacent ends of the fixed member A 30 and the movable member B, and fastened thereto by screws E through the front face of the attaching members. Near the outer side of the attaching member C is arranged a vertically disposed pivot F on which is 35 mounted to swing the U-shaped link G, and a similar link G^1 is mounted to swing on a vertically disposed pivot F^1 attached near the outer side of the attaching member D. The link G crosses the link G^1 and is pivoted therewith by means of a pin H which 40 has no connection with the attaching members C and D, and the free end of the link G extends into the attaching member D while the free end of the link G^1 extends 45 into the attaching member C. Near the inner side of the attaching member C is arranged a vertically disposed pivot I on which is mounted to swing the link J, and a similar link J^1 is mounted to swing on a 50 vertically disposed pivot I^1 attached near the inner side of the attaching member D. The free end of the link J is pivotally connected to the link G^1 near the free end thereof by means of a pin K, while the free end 55 of the link J^1 is pivotally connected to the link G near the free end thereof by means of the pin K^1 . It is understood that the pins K and K^1 have no connection with the attaching members C and D. As shown in 60 Figs. 14 and 15, the series of links G, G^1 , J and J^1 may be arranged one over the other and connected in the manner described so as to provide any desired strength according to the use of the hinge on light or heavy 65 doors. It is understood that the links G and G^1 are the connecting links and the links J and J^1 are the guiding links. The links G and G^1 by their connection with the attaching members C and D and with each other by means of the pin H form the connection between the attaching members C and D. The links J and J^1 by their connection with the attaching members C and D and the connecting links G and G^1 form guiding links to insure working in unison of the 70 connecting links and uniformly separate and bring together the attaching members, and prevent binding of the hinged members in opening and closing the door. By the arrangement described each attaching member C or D is provided with a pair of links G, J or G^1 , J^1 arranged in inverse order to each other and one of the links in each attaching member is connected with both of the links in the other attaching member. 75 It will be noted that the guiding links J and J^1 are connected and arranged in the attaching members C and D inversely to the connecting links G and G^1 . Whereas the connecting links G and G^1 are secured near 80 the outer side of the attaching members with the swinging portions directed toward the inner side of the attaching members, the guiding links J and J^1 are secured to the inner side of the attaching members 85 with the swinging portions directed toward the outer side of the attaching members. When the door B swings into open position the links G, J and G^1 , J^1 swing in their respective attaching members toward the 90 front face thereof, and the connecting links G and G^1 overlie each other at the time the door is swung into a completely open position so that the door is firmly supported 95 while in open position. The connecting 100 links G and G^1 are provided with notches G^2 and G^3 of which the notch G^2 is adapted to be engaged by the pivot pin F while the notch G^3 is adapted to be engaged by the 105 pivot pin F^1 at the time the door swings 110 into open position as indicated in Fig. 13, and assists in relieving the hinge of undue strain and in limiting the opening movement of the hinge. The connecting links G and G^1 are also provided with lugs or stops 115 G^4 and G^5 formed of the ends of the said connecting links beyond the pivot pins K and K^1 , of which the lug G^4 is adapted to be engaged by the pivot pin I while the lug G^5 is adapted to be engaged by the pivot 120 pin I^1 at the time the hinge swings into open position as indicated in Fig. 13, and assists in relieving the hinge of undue strain and also acts as a stop to limit the opening movement of the hinge, and is also designed 125 to prevent the pins K and K^1 from swinging beyond dead center of pins I, H or I^1 , H when the hinge swings into open position as shown in Fig. 13.

Excepting in the largest size hinge for use 130

on heavy doors, it has been necessary heretofore to use grooves or slots as guiding means for the connecting means in the particular type of hinge shown in Figs. 11, 12, 13, 14 and 15. These grooves or slots are formed in the attaching members, and the connecting means slide therein during the operation of the hinge. The use of these grooves or slots were necessary to properly open the hinged members without binding, and as stated above, only in the very largest size was it possible to dispense with the grooves and use instead movable guiding means or links. The type of guiding link used is similar to that shown and described in Letters Patent of the United States granted to me Aug. 25, 1914, No. 1,108,308 and in prior patents granted to others, and is secured to the attaching members nearest the outer side of the same and on the same side thereof to which the connecting means are secured, and the said guiding links mounted in each attaching member swing in the same manner and direction as the other links in the said attaching member. In my invention, as shown in Figs. 11, 12, 13, 14 and 15 I propose to attach my guiding means near the inner side of the attaching members, with the direction of its length arranged inversely to the connecting means. By this arrangement I am enabled to guide the connecting means in such manner as to cause the hinge to open and close without binding the hinged members, in short, causing sufficient clearance to be maintained to prevent the swinging member from touching the stationary member during the operation of the hinge, and removing the necessity of grooves or slots in this type of hinge in all sizes from the very smallest to the largest made.

The hinge shown in Fig. 16 is a modification of the hinge shown in Letters Patent of the United States granted to me August 25, 1914, No. 1,108,308. Instead of the guiding links shown and described in the said patent, I substitute the inverted guiding means which is a part of this invention. The links L, L¹, M and M¹ correspond with the links H, H¹, J and J¹ of the above mentioned patent and are secured to the attaching members and to each other in the same general manner. The inverted guiding links N and N¹ are connected to the free ends M² and M³ of the links M and M¹ and to the inner side of the attaching members C and D.

In the Letters Patent of the U. S. granted to me Sept. 24, 1912, No. 1,039,628, I show and describe connecting links slidably mounted one over the other and pivotally connected to each attaching member and guided in grooves connected with the other attaching member. The inverted guiding means which is a part of this invention may be applied to the hinge described in the above mentioned patent in lieu of the grooves shown, enabling

the hinge to be constructed with sheet metal attaching members as shown in Figs. 4, 5, 10, 14 and 15.

In the foregoing I refer to the guiding links as "inverted," "inversely disposed," "inversely connected," arranged in "inverse order." By this I mean guiding links turned in upside down fashion to the other links or turned to a contrary direction, or to be still more explicit, guiding links so connected to the attaching members that when the hinge is in closed position, the swinging portions of the said guiding links are directed toward that side of the attaching members to which the other links are connected.

Although I have described my invention as shown in the accompanying drawings, other changes in and modifications of the construction herein shown and described may be made within the scope of the appended claims without departing from the spirit of my invention or sacrificing its advantages.

Having thus described my invention, I claim as new and desire to secure by Letters Patent:

1. A hinge for connecting the swinging and stationary portions of the device on which it is used; said hinge consisting of two attaching members, a link swingingly connected at each side of each attaching member, and means connecting the said links with each other.

2. A hinge for connecting the swinging and stationary portions of the device on which it is used; said hinge consisting of two attaching members, two separated links swingingly connected to opposite sides of each attaching member, means connecting the links of each attaching member with each other, and means connecting the links of each attaching member with the other attaching member.

3. A hinge for connecting the swinging and stationary portions of the device on which it is used; said hinge consisting of two attaching members and a connection of movable links; the said connection arranged in and pivotally connected with the attaching members so that the swinging portions of the pivoted links in each attaching member are inversely directed toward opposite sides of the attaching members at the time the hinge is in closed position.

4. A hinge comprising two attaching members arranged one for attachment to a fixed part and the other to a movable part of the device on which the hinge is used, links swingingly mounted in each attaching member and disposed and actuated inversely to each other but swinging in the same direction during the opening and closing of the device on which the hinge is used, means connecting the links of each attaching member

with each other, and means connecting the links of each attaching member with the links of the other attaching member.

5. A hinge comprising two recessed mortised members and movable means pivotally connecting each side of each attaching member with the diagonally opposite parallel side of the other attaching member.

6. A hinge comprising two attaching members, movable means pivotally connecting each side of each attaching member with the diagonally opposite parallel side of the other attaching member, and means connecting the pivotally connecting means with each other at the point where said connecting means intersect each other.

7. A hinge comprising attaching members, a connection for connecting the attaching members with each other, guiding means pivoted to the attaching members and to the said connection, and means connected to the said connection and designed to engage the pivot connecting the guiding means to the attaching members in such manner as to limit the opening movement of the said guiding means.

8. A hinge comprising attaching members, links pivotally secured at both sides of each attaching member, and links connecting the links secured at one side of the attaching members with the links secured at the other side of the attaching members.

9. A hinge comprising two attaching members, a main connecting link swingingly secured to one side of each attaching member, an inverted guiding link swingingly secured to the other side of each attaching

member, and a supplementary connecting link connecting the main connecting and guiding links of each attaching member; all 40 of the links being adapted to swing or move toward and away from the front face of the attaching member to which they are secured during the opening and closing movements of the hinged members. 45

10. A hinge comprising two attaching members, a main connecting link mounted in each attaching member and crossing each other, the free end of the link mounted in each attaching member connected to an inverted guiding link mounted in the other attaching member, a supplementary connecting link connecting the main connecting and guiding links of each attaching member, and lugs or stops forming a part of the supplementary connecting links and adapted to limit the movement of the guiding links when the hinge is moved into open position. 55

11. A hinge comprising two attaching members, main links connected to each other and to the attaching members, guide links connected to the attaching members and to the main links, and means whereby the pins or pivots connecting the main links to the guide links are prevented from moving beyond an imaginary line drawn between the pin or pivot connecting the main links to each other and the pins or pivots connecting the guide links to the attaching members. 60 65
